(57) **CLAIM**

The ornamental design for a microphone isolation shield, as shown and described.

DESCRIPTION

FIG. 1 is a front and top perspective view of a microphone isolation shield, showing my new design;
FIG. 2 is a rear and bottom perspective view thereof;
FIG. 3 is a rear and top perspective view thereof;
FIG. 4 is a front elevation view thereof;
FIG. 5 is a rear view thereof;
FIG. 6 is a left side elevation view thereof;
FIG. 7 is a right side elevation view thereof;
FIG. 8 is a top plan view thereof;
FIG. 9 is a bottom plan view thereof;
FIG. 10 is an enlarged view of a portion of the microphone isolation shield labeled **10** of FIG. 2;
FIG. 11 is an enlarged view of a portion of the microphone isolation shield labeled **11** of FIG. 2;
FIG. 12 is a front and top perspective view of the microphone isolation shield shown in a state of use;
FIG. 13 is a rear and bottom perspective view thereof;
FIG. 14 is a front and top perspective view of the microphone isolation shield shown in another state of use; and,
FIG. 15 is a rear and top perspective view thereof.
The broken lines depict portions of the microphone isolation shield in which the design is embodied that form no part of the claimed design.

1 Claim, 15 Drawing Sheets
